UNITED STATES PATENT OFFICE.

JAMES R. LISTER, OF CLINTON, MASSACHUSETTS, ASSIGNOR TO ROUBAIX MILLS, INCORPORATED, OF NEW YORK, N. Y., A CORPORATION OF NEW YORK.

WEAVING.

Application filed December 1, 1923. Serial No. 677,932.

This invention relates generally to the manufacture of woven fabrics and involves (1) a method of producing a fabric in which wefts and warps are so associated and interengaged that one or more strands of one forms a core for one or more strands of the other and coordinate a fabric produced by such method; (2) the employment of such fabrics for the manufacture of tires, 10 collars, etc. and (3) a new method of producing a looped or pile fabric and the fabric produced by such method.

While in the description of my invention as hereinafter to be given, it may appear that the first of these phases of my invention, namely, the production of a fabric with core threads therein, is merely a step in the production of a looped fabric, it will be understood that the two are coordinate except as otherwise specifically stated and that while the looped fabric to be herein-after described may involve preliminarily the production of the fabric with the core thread therein as herein above referred to, 20 it will be understood that the production of such fabric itself may be the ultimate object desired of attainment.

I have employed the terms "core pick," "core strand" and "core weft" not as having any special significance but merely for convenience to refer to the pick or weft strand which is numbered P² in the drawings and to readily distinguish this pick from the other or ground picks in as short 30 and simple way as possible. When such expressions therefore are used therewith in this application and particularly in the claims, it will be understood merely as having its generic significance as a pick unless the context imparts or necessitates some limiting effect to such expression or word.

One of the methods hitherto practiced for the production of the loop or pile fabric has been by means of the use of what has been 40 known as pile wires, and in this method there is employed a number of pile wires which are introduced at predetermined points and which are so associated with the loose warps that they cause these warps to loop about these pile wires so that upon their withdrawal from the fabric, there will be left a loop in the warp at each point where the loose warp was engaged therewith. This method of manufacturing pile 50 fabric is a comparatively slow one and not

only requires the use of pile wires with the consequent expense due to original investment, replacement and repair, but also requires a floor space that is substantially twice that required by an ordinary loom 60 since there must be to the side thereof sufficient space for the transverse movement of the pile wires into and out of association with the warps.

In an attempt to supplant or overcome 65 these objections to the pile wire method of production, there was developed what is known as the "terry motion", in which the loops in the warp are produced as follows:

A number of picks or weft strands, two 70 for instance, are introduced or shot across by the shuttles. The lay, by means of suitable mechanism is caused to make a short stroke with the result that these picks are not beaten up to the fell. Upon the addition of a further and additional pick, the mechanism causes the lay to give a full stroke and beat up the picks of the fell. The picks slide along the tight or ground warps, but the friction of the picks against 75 the loose warp, commonly called the terry warp, causes the latter to be carried along by the picks as they are beaten up, with the result that that part of the loose warp in advance of the picks is buckled or forced 80 out of the general level of the weave and is thus formed into loops. While this terry motion does overcome most of the objections to the employment of the pile wire method, it nevertheless gives rise to a number 85 of new objections among which are the following:

First the loops are not definitely formed by which is meant that the amount of buckling of the loose warp depends upon the 90 firmness of the frictional grip of the picks upon the loose warp and this frequently differs upon the individual warp strands due to slight variations in tension or slight variations in the spinning of the strands 95 with the result that the loop formed by one loose warp strand will be larger or smaller than that formed by an adjoining loose warp strand with the result that more or less irregularity in the forming of the loops 100 is an inherent defect of this method.

Second, there is nothing to positively control the direction of the buckling of the loose warp with the result that individual loops may and frequently do take a 110

direction the reverse of that taken by the general loop pile of the fabric, causing skips or omitted loops upon the face of the fabric and loop strands below the body of the fabric a defect which it is very desirable to avoid in highly finished fabrics.

Furthermore, the use of this method of making loop fabrics requires special mechanism to vary the beat-up of the lay to which 10 the term "terry motion" has been generally applied and will be so referred to hereinafter. This mechanism is an additional installation which involves considerable original cost and also necessary replacements and 15 repairs. In addition to this, the change from the operation of the loom for the purposes of plain weaving to that of terry weaving is one that involves labor, expense and lost time.

20 Jacquard patterns, plush and carpet goods cannot be made practically by the terry motion, for reasons that are understood by those skilled in the art, and the pile wire method must be employed for the production of 25 such fabrics.

Attempts have been made hitherto to obtain the advantages of the pile wire method, namely, the formation of a definite loop in a definite direction by pile wires by employing 30 methods in which core strands of textile material are introduced by means of shuttles, these core strands serving as supplementary picks which are either removed from the weave in any preferred or desired manner 35 as by being pulled out, or are made of a material which permits of their removal by a carbonization process without affecting the main fabric structure. Such attempts have been of various characters such as the introduction of supplementary picks beneath 40 the loose warps in a plane above that of the ground weave, the supplementary picks being supported above said plane by the use of instrumentalities such as distenders or 45 platforms and the loose warps being laid thereabove and being woven into the ground weave on both sides thereof or by the introduction into the ground weave of core strands of greater cross-sectional area than 50 that of the ground weave. In both such cases, it will be understood that the displacing of the extra picks on the one hand or their increased thickness on the other will necessitate an extra length of the loose warp 55 threads being fed off the warp beams to be looped about such core strands so that with their removal in a manner as above pointed out there will be left the extra lengths in 60 the form of loops in the warp thread thus formed.

These methods of employing a core of textile material which is formed into picks in the same manner as are the usual picks, it will be observed, call either for weaving 65 the core picks as part of the ground weave,

in which case the removal of said core pick will show in the resulting weave, or call for the use of some additional supplemental mechanism for supporting these core picks in a plane above that of the ground weave. 70 When I attempted to employ such processes, I have discovered that where an extra support is used to maintain the core picks in their elevated plane, the withdrawal of such support necessarily renders less efficient the 75 action of the core pick in serving as a core about which to form the loops. For these reasons, the loops thus formed about such cores are not definitely formed in the sense in which I have above set forth and to which 80 further reference will be made hereinafter.

In addition, at the present time, in the textile trade, especially in the markets for so-called "novelty fabrics", changes in styles are frequent and difficult to forecast, with 85 the result that the great desiderata in mills supplying such markets are processes by which the ordinary loom equipment can be used without making time consuming and expensive changes, or the purchase of expensive auxiliary devices and attachments to meet what may in the end prove to be an evanescent demand of the trade.

As my invention in one of its phases is 90 directed to the production of a fabric on an ordinary plain fabric loom, I will premise that the ordinary plain fabric loom is provided with warp beams upon which the strands to form the warp are wound, there 95 being one or more of these according to the number of warps to be used in the weave. The warp beams are controlled by let-offs by means of which the feed of the warp to the 100 weave is controlled, tensioning devices being provided by means of which the tightness or 105 looseness of the warps are controlled.

Heddle frames and harness control the shedding of the warp; a reed spaces the 110 warp strands; a lay beats up the weft to form with the warps the web which constitutes the fabric; a shuttle race or rail guides the weft shuttles between the warp sheds; a picker mechanism propels the shuttles along the shuttle race or rail; a cloth beam winds up the woven fabric and a 115 take-up controls the movement of the cloth beam. Pattern chains, jacquard cards, etc., are commonly provided to control the weave, driving mechanism, gearing by which the 120 operation of the various parts of the loom is correlated and controlled are all common features of such a loom, well known, and their operation fully understood by those skilled in the art, and are, therefore, not further illustrated or described, and wherever in this specification any of the above 125 enumerated parts of a loom are mentioned or its function mentioned without description of how this function is to be performed, it is to be understood that such part is an 130

ordinary part of such a loom and the function of such a part is performed in an ordinary and familiar method.

In my method of manufacturing the fabric, I employ a plain fabric loom of the character above set forth in such a way that a loop is not only caused to be definitely formed about a core weft but that such core weft is in the form of an extra core pick 10 which is so positioned and associated with the ground weave that while on the one hand it is wholly independent of the ground weave yet on the other hand it is positioned definitely with relationship thereto and is 15 also supported thereby.

In the operation of an ordinary plain loom of the character which is described above, the lay beats up the weft to the fell which is the last pick woven into the web or the fabric 20 and the parts are so associated that the lay moves from a predetermined point to a predetermined point, and during such movement contacts with the pick which has just been shot across in front of it and beats up 25 said pick against the fell. As will be understood the lay in this beating up process moves the pick from the point at which it has been put down right up against the fell, and this I will term the effective throw or 30 beating up of the pick since it is that part of the movement of the lay which is effective to move the pick. After each operation of the lay, i. e. the beat-up of a pick which is woven into the fabric and forms the fell 35 thereof, the take-up mechanism is operated to advance the woven fabric and along with it the fell so as to make room for the next pick which is to form the new fell, and as will be understood, if the movement of the 40 take-up is departed from in any respect whatsoever, the position of the fell will be altered thereby and the spatial or positional relationship of the fell with reference to the next pick which is beaten up will be 45 varied; for instance, if the take-up should be operated to move the woven fabric a greater distance than the normal immediately before a new pick is thrown in, the ordinary beat-up of the lay will move this 50 pick to a position short of the fell so that there will be a space in between; so also if a pick is introduced at any time which is of materially less cross sectional area, the normal beat-up of the lay will not move this 55 pick up against the fell, but will cause it to be positioned a distance short of the fell, depending upon the amount of decrease in its diameter; so also if the beat-up of the lay is varied as by causing it to move for a lesser 60 distance, it will naturally position the pick short of the fell; in other words, the effective beat-up of any particular pick is dependent upon what might be termed three 65 variants, namely, first, the movement of the lay; second, the take-up of the fabric; and

third, the thickness of the individual pick thrown in, and where these three factors are predetermined so as to give an ordinary ground weave and are maintained constant, an ordinary ground weave will be produced 70 and maintained.

In the above examples as given each of the factors will vary so as to produce a less effective throw of the pick; that is, a throw which causes the pick to fall short of the 75 fell. On the other hand, any one or more of these variants may be varied so as to increase the effective beat-up of the lay, that is, to cause the lay to move the cloth not only up against the fell but to tend to move it beyond. For instance, by stopping the take-up altogether just before a pick is beaten-up, the lay will move this pick not only up against the fell but will tend to move it a distance beyond and as the fell is already part 80 of the woven fabric and is maintained fixed by the cloth beam, this pick being supported, as will be set forth more fully in the specification, on the tight warps, will be moved not only up against the fell but in the continued movements of the lay will actually move up and over the fell and position itself thereabove and upon the fabric already woven at a point dependent upon the change 85 in variant referred to; so also an action of this character but to a lesser extent could be attained by moving the take-up to a decreased extent rather than by merely stopping it, and a decidedly increased action can 90 be attained by reversing the take-up or the cloth beam or employing any other method by which the fabric is caused to be moved in a reverse or backward direction. A somewhat similar effect in the effective beat-up of the pick could be attained by varying the 95 effective thickness of the pick, for by increasing the thickness of the pick substantially or by employing more than one core pick in the same shed, the beat-up will tend to 100 squeeze it upwardly on top of the fell and a somewhat similar effect could be attained by increasing the actual movement of the lay 105 when beating up a predetermined pick.

I have found by relying upon the stopping of the take-up as one of the important factors in the production of my new fabric, I am not only enabled to obtain a ground weave which is of uniform density, and will 110 not show on its lower face the employment of my method, but one in which the core pick will be moved over most effectively on the fabric and maintained thereon.

My invention, therefore, broadly involves the employment of a core weft or pick and so controlling one or more of the variants as to cause this pick to position itself above the fell of the ground weave. For the production of the weave embodying the invention described herein, I have the loose warps anchored between spaced picks and floated over 125 130

the picks therebetween, and I give to the loose warps intermediate these locking picks the extra length required by the loop by causing the movement of the core pick over the fell as already referred to to serve to pull upon the loose warp so as to provide this excess length, thus dispensing with the necessity for employing any let-off mechanism. In other words, in the general method employed by me I first lock the loose warp into the ground weave to form the rear end of the loop which is thus anchored into the ground weave and introduce the extra or core pick beneath the loose warp and above the tight warps and when this extra or core pick is beaten up against the fell and upon and over the woven fabric in the manner already referred to it will necessarily pull off with it an extra length of the loose warps in a manner that will be understood as the specification is read and the drawings analyzed. The loose warp is then floated over one or more of the succeeding picks and then is again caused to be locked into the ground weave to form the front of the loop which is thus anchored to the ground weave. As a result of this arrangement, I obtain, first, from the standpoint of one of the phases of my invention, namely, that in which the core pick is to be retained, a loop which is grounded in the fabric by means of its interlock with spaced picks and in which the loop is definitely formed and maintained somewhat in the form of a ridge by the core pick, and secondly, from another phase of my invention, namely, that in which the core pick is removed, the loop which is locked into the ground weave by the spaced picks as already stated has its extra length and also its shape predetermined by the core pick which is to be removed. In addition by increasing the effective throw of the core pick, the extra length of the loose warps to provide the loops is obtained by the action of the core pick thereon in a manner that has been referred to and will be explained more fully hereinafter. My invention therefore also broadly involves the arrangement by which the core pick is manipulated or operated on so as to serve to pull off the excess length of the loose warp as desired and additionally involves the arrangement whereby this core pick is introduced immediately after the loose warp is locked into the ground weave and additionally the arrangement whereby the loose warp is thereafter floated over one or more picks before it is locked into the ground weave.

As has already been stated, I employ for varying the effective beat-up of the core pick, a core pick which is of substantially increased diameter and which as stated it may be desired to remove by one or other of the processes above referred to and that for this

purpose I may employ a core pick made of 65 cotton. I have, however, found that where this core pick is made of a cellulose fibrous base, such as paper, that not only is the core pick which is to be removed less expensive but due to the character of this material and to the extent to which it permits of treatment I can obtain a core pick which is of relatively greater stiffness and rigidity so that it serves its function as a core pick to be removed much more efficiently, 70 at least from the standpoint referred to. Furthermore, in the use of such a pick for the manufacture of carpets, etc., by my method the pick could be colored and made to serve as a fixed part of the weave. 80

I have also found by employing a core pick which is of the character of rigidity such as is attainable by making it of a thickness and material as set forth, I can employ my method for the manufacture of jacquard 85 patterns, plush and carpets, since thereby I attain all the advantages of the pile wire method.

As will be understood the fabric produced by the employment of a core pick as described, will be of a character that might be termed "corded" and such "corded" fabric may serve effectively for various purposes such as in the manufacture of cord tires, in which by placing the core picks closely adjacent, there could be produced a fabric for cord tires in which there would be a firm ground and a series of cords placed close together on the face of the fabric and bound securely to the main cloth. In employing my 100 fabric for cord tires, I superimpose layers of my fabric cut so as to position the "cords" either longitudinally thereabout or obliquely thereacross as on the ordinary cord tire with the successive layers presenting the "cords" 105 at an angle to each other somewhat as in the conventional type of cord tire construction.

I can also employ my fabric for the manufacture of the type of men's collars now in vogue and which are of a more rigid and stiffer material than a soft collar, but which when starched are not as stiff as the type known as "stiff" collars. By making the under side of the ground fabric the outside of the collar, a smooth effect could be attained or by reversing the arrangement, a corded effect could be had.

My invention, therefore, further involves the employment of a core pick made of a material such as that mentioned and which permits of its being given a relative rigidity and stiffness, and where its ready removal therefrom is desired, the core pick used may possess further a characteristic which will permit of this.

For the attainment of these objects and of such other objects that may either herein-

after appear or be pointed out, I have illustrated the production of a weave embodying my invention in the drawings wherein—

Fig. 1 is a vertical section through the 5 weave taken parallel to the warps with core picks inserted;

Fig. 2 is a similar view of the relationship of a loose warp thread to the picks with the tight warp threads omitted;

10 Fig. 3 and Fig. 4 are views similar to that of Fig. 2, but each showing the relationship of a different one of the tight warp threads to the picks;

15 Fig. 5 is a top plan view looking down upon the weave of Fig. 1;

Fig. 6 is a section through the weave similar to that of Fig. 1 with the core picks removed;

20 Fig. 7 and Fig. 8 are sections similar to that of Fig. 1 through modified forms of the weave; and

Fig. 9 is a section showing the plane in which the core pick is laid.

Upon viewing the drawings it will be observed that I have illustrated in Figures 1 to 5 a weave in which there are employed three warps, two of which are made up of tight warp threads and the third, of loose warp threads, and four wefts, three of which are made up of ground picks and the fourth of which is made up of core picks, and as I have illustrated in the Fig. 6 of the drawing a weave such as that illustrated in Figures 1 and 5 with the core picks removed, it will be understood, (first) that the weave illustrated in the drawings and made up of the picks and threads as just mentioned is so shown and described merely as showing one embodiment and that in so far as my invention as claimed permits, such specific disclosures are intended to be only illustrative and not limitative; and (secondly), that while the fabric of Fig. 8 may at times be herein referred to and may in fact be intended as the ultimate completed fabric, yet it will be understood that the fabric of the other figures may also be the ultimate completed fabric and that therefore any reference to removing of the core picks in the fabric of Fig. 50 1 to produce the fabric of Fig. 8 is not intended to mean that the fabric of Fig. 1 is not a completed fabric in itself, but that by such removal another and additional fabric is produced.

55 I will now describe how I employ a plain loom of the character such as set out above for the manufacture of my new weave employing my new method referred to.

Upon viewing Figure 1, it will be observed that I have illustrated my invention in a weave in which I employ three warps, two of which are tight warps and will be hereinafter referred to as tight or ground warps, and one of which is a loose warp and from which the loops are to be formed and

which will be referred to as the loose or looped warp; and in addition I employ four wefts, three of which form the ground weave and will be hereinafter referred to as ground weft threads or picks and a supplemental weft thread about which the loose warp is looped and which will hereinafter be referred to as the core weft or pick.

In my method I form the ground weave and associate therewith in the manner shortly to be pointed out one or more loose warps and core picks in such a manner as to cause the production of the weave of Fig. 1, and so that the manner of my employment of the ordinary type of plain fabric loom may be understood, I will start with the beating up of the pick P^4 in Fig. 2, opposite which there appears the arrow, it being understood that the fell is already formed about the pick P^3 to the right thereof. As this pick P^4 is beaten up, the tight warp W^1 is shed up and the tight warp W^2 shed down, so that this pick P^4 is positioned therebetween and as for the next beat-up, the shed of these two tight warps is reversed the pick P^4 is locked between the warps and in the ground as will be understood and as will be seen from the drawings, and will therefore serve as what might be termed an anchor pick. The shed is then reversed (as already stated) for the beat-up of the next pick P^1 . The warp W^2 now being up and warp W^1 being down so that the pick P^1 is above both tight warp W^1 and the loose warp W^3 and is beneath the tight warp W^2 . The shed is now changed so that the tight warps are both down and the loose warp is up for the introduction of the core pick P^2 . This core pick P^2 is made of a diameter that is many times greater than that of the ordinary ground picks, and as it is beaten up, the lay will not only tend to move it up against the pick P^1 which is already woven into the fabric and forms the fell thereof, but will tend to move it therebeyond, and in such movement, the tight warps W^1 and W^2 which are therebeneath will not only form a support therefor but will also serve to guide this core pick P^2 upwardly and to some extent over upon pick P^1 , and in order to still further increase the effective throw of this core pick by the lay so as to cause it not only to position itself above the pick P^1 but to carry the loose or loop warp W^3 with it, I stop the take up of the cloth after the beat-up of pick P^1 so that the fell formed about the pick P^1 is not moved as the result of which it necessarily follows that the effective throw of the core pick will be still further increased and its resulting throw along the tight warps W^1 and W^2 and up and over the pick P^1 will be also increased; in other words, the operation as a result of the variation in the effective throw of the core pick brought

110
115
120
125
130

about in the manner set forth will cause this core pick to position itself above and to be supported upon the fabric already formed and will also pull with it, as it were, 5 the loose warp which is disposed thereabout and will thus tend to form at least to the right thereof a definite loop formation, the completion of which will take place as shortly to be pointed out. The shed of the 10 two tight warps is then reversed for the introduction of pick P^3 , restoring them to what they were when pick P^1 was introduced, so that due to the fact that the core pick P^2 is raised up and out of the ground 15 weave even though a reversal of the picks took place between the introduction of picks P^1 and P^3 yet in fact they are in the same shed. The shed of the tight warps are again reversed for the introduction of pick P^4 20 which as already described forms the anchor pick and for the introduction of the next pick, namely pick P^1 , not only is the shed of the tight warps reversed but the loose warp is shedded beneath this pick so that 25 not only will this pick P^1 serve to anchor the loop formed about the core pick P^2 but will also tend to tighten said loop about said core so that thereby a loop is predeterminedly and definitely formed about said 30 core pick P^2 .

Upon viewing Fig. 1, it will be observed that the weave comprises (1) a ground weave made up of the two tight warps W^1 and W^2 and of the ground picks P^1 , P^3 and P^4 which 35 are interlocked therewith to form the ground weave. The loose warp W^3 is interlocked in this ground weave by means of the ground pick P^1 , the loose or terry warp being shedded above picks P^3 and P^4 . It will also 40 be observed that the loose warp W^3 is looped about the core pick P^2 , which is positioned above the ground pick P^1 and serve not only to force the looseness of the loose warp W^3 over the ground pick P^1 , but also serves to 45 cause the loop and the loose warp W^3 to be definitely formed thereabout and to conform to the configuration and dimensions of the core pick P^2 . It will further be understood that the ground pick P^2 in its movement 50 above the fabric already woven, will not only serve to pull the necessary extra length of loose warp thread from off its beam, thus dispensing with the necessity for any special let off mechanism therefor, but will also pull off only sufficient extra length as is required by that particular core pick.

I have thus produced a fabric illustrated in Figures 1 and 5 which is of a character that might be termed a combined ridged and 60 looped fabric, and if desired this fabric, after going through the necessary finishing operations, may be used in the form in which it has been finished, as already described and as shown in these figures.

65 It will be understood, of course, that one

of the essential features in the production thereof is the variation in the effective throw of the core pick which as already mentioned may be attained by the variation in any one or more of the factors that go to determine 70 this effective throw and which in the description thus far given involves the employment of a very much thicker core weft and in a variation in the action of the take-up, which I have stated for the purposes of illustration is secured by stopping the take-up before this core pick is thrown in. 75

The take-up is generally controlled by a gear which has upon it as many teeth as there are picks to the inch and which gear is moved one tooth after each throwing in of a pick so as to move the cloth for a length corresponding to the increase in length of the woven cloth, upon the insertion of an additional pick and this step by step operation of the gear is secured in a well known manner and need not be described or illustrated here. Unless this gear is held against reverse movement, the weight 80 of the parts and the tension of the fabric 85 and of the beams will be such as to cause it to move back reversely for the distance for which it has been advanced and for preventing this, a detent pawl is generally associated therewith in a well known manner 90 so as to prevent such reverse movement. I have attained the desired stopping of the take-up by rendering this holding pawl inoperative so that when the gear is advanced 95 for the take-up it will move back to its 100 original position with the moving pawl so that there is no take-up and in effect the take-up is stopped. This I attain by attaching a string to this holding pawl which is connected to a jack or lever on the head 105 motion and which is operated in exactly the same manner as is the harness, that is, when the pawl is required to be lifted so that there shall be no take-up, the lever is forced up and draws forward and upward 110 the cord attached to the pawl on the following pick. It drops down again and operates in the regular way for three picks when the same operation is repeated.

Where, however, it is desired to produce what is wholly a looped fabric from the weave of Figure 1, this can be attained by removing the core strands or picks therefrom in any desired or preferred manner as by pulling them out or by carbonization, 115 which can be done by making the warps and the ground weaves of one character of material such as of animal fibres and making the core weft of a character of material such as vegetable fibres so that by chemical treatment of the core strand before weaving or of the fabric as a whole after the weaving process is completed, the core strand of vegetable fibre can be removed by carbonization 120 and washing. For this purpose the core 125

strand may be made of cotton fibre which is acted upon by a chemical such as hydrochloric or sulphuric acid to permit of its removal in the manner set forth.

5 I have found, however, that I may use core strands of paper or a paper composition which can be removed substantially in the same manner as can a cotton pick yet possesses certain advantages which may suggest the advisability of its use, and among these are the fact that a pick made of paper fibre will be stiffer than one made of cotton and will thus permit of the formation of the desired loop in a more definite manner and 15 at the same time the cost of such fibre is less.

By the removal of this core in any desired or preferred manner such as set forth, I obtained the fabric of Figure 6, which, while it in many respects resembles the character 20 of loop fabrics hitherto produced, yet has its loops formed definitely and uniformly both as to size and contour and shape and results in a fabric in which the loops are all 25 symmetrically arranged on either or both sides of the fabric as may be desired.

Upon viewing the various figures of the drawing, it will be observed that due to the manner in which my fabric is woven, the back of the ground weave will be of uniform 30 texture and will not indicate the presence of the superposed associated picks P^2 and loops in the warp nor will the fabric when the pick P^2 is removed vary in any respect from such a fabric woven by a method such as 35 the terry motion except as already pointed out.

Upon viewing the Figure 1 of the drawing, it will be observed that the pick P^2 is superposed above the pick P^1 and that the 40 loose warp W^3 is anchored in the ground weave beneath; the pick W^3 then passes around and thereabout to a position between the two picks and then in a reverse direction around the upper pick P^2 around and 45 thereabove and is then floated over picks P^3 and P^4 and is again anchored in the next pick P^1 .

It will be further observed that due to the manner of association with picks P^1 and 50 P^2 , the loose warp forms what is in effect an ogee curve about these picks. As has already been explained, this effect is produced by the fact that in my method the pick P^2 as it is beaten up by the lay moves into contact with the loose warp adjacent its point 55 of anchorage in the ground weave beneath the pick P^1 and in its further movement up and over the pick P^2 carries the loose warp with it so that in this manner I can dispense 60 with any mechanism for letting off the loose warp and can depend wholly upon the pulling action of this pick P^2 to supply the extra length of warp necessary to form the loop.

In Figure 7 I have illustrated a modification in which the loose warp W^3 has been

anchored successively beneath the two ground picks P^1 , P^5 , and over P^6 instead of beneath one pick as in Figure 1. I thereby attain a firmer anchorage for the loose warp threads which will be of particular 70 utility where a cut pile fabric is desired.

In Figure 8 I have illustrated a modification in which I employ the two core picks P^2 instead of the one core pick P^2 of Figure 1. These two picks are each laid in successively as described in connection with the pick P^2 of Figure 1. I thereby secure a loop 75 which is more uniformly shaped and further am enabled to use less weight in the core picks employed. 80

Having thus described my invention and illustrated its use, what I claim as new and desire to secure by Letters Patent is:

1. The process of weaving a fabric which comprises weaving a ground fabric of tight 85 warp threads and ground weft threads and interlocking a loose warp thread therewith, laying in a core pick over said ground warp threads and under the loose warp thread and causing said loose warp thread to be positioned over said core pick and one or more of the ground weft threads.

2. The process of weaving a fabric which comprises weaving a ground fabric of tight 95 warps and ground wefts and interlocking a loose warp thread therewith, laying in a core pick over said ground warps and beneath the loose warp thread and then causing said core pick to be moved over on top of the fabric. 100

3. The process of weaving a fabric which includes the step or steps of weaving a ground fabric of tight warps and of ground wefts and interlocking a loose warp thread therewith, laying a core pick over tight 105 warps and beneath the loose warp thread, and causing said core pick to be given a movement forwardly and upwardly of the plane of the ground weave so as to cause an extra length of the loose warp thread to be 110 fed from the loose warp beam.

4. The process of weaving a fabric which comprises weaving a ground fabric of tight warps and ground wefts and interlocking a loose warp thread therewith, laying in a 115 core pick above the ground warps and below the loose warp thread and varying the effective beat-up of said core pick.

5. The process of weaving a fabric which comprises weaving a ground fabric of tight 120 warps and ground wefts and interlocking loose warp threads therewith, laying in a core pick above the ground warps and below the loose warps and increasing the effective beat-up of said core pick. 125

6. The process of weaving a fabric which comprises weaving a ground fabric of tight warps and ground wefts and interlocking loose warp threads therewith, laying in a core pick above the ground warps and be- 130

low the loose warps and increasing the effective beat-up of said core pick by employing a core pick of increased diameter.

7. The process of weaving a fabric which comprises weaving a ground fabric of tight warps and ground wefts and interlocking loose warp threads therewith, laying in a core pick above the ground warps and below the loose warps and increasing the effective beat-up of said core pick, by employing a core pick of increased diameter and stopping the take-up.

8. The process of producing an extra length on a loose warp thread to permit of the formation of a loop therein, which includes the step or steps of anchoring the loose warp thread on the ground weave, and causing a weft thread to move against said loose warp thread adjacent its point of anchorage and in a direction to cause an extra length thereof to be let off the loose warp beam.

9. The process of providing an extra length on a loose warp thread, which includes the step or steps of anchoring the loose warp thread in the ground weave and causing a pick to move against said loose thread adjacent its point of anchorage and upward and over said point of anchorage.

30 10. The process of providing an extra

length on a loose warp thread to permit of the formation of a loop therein, which includes the step or steps of anchoring the loose warp thread in the ground weave, and causing a pick of greater thickness than that of the ground picks to move against said loose thread adjacent its point of anchorage and in a direction to cause an extra length thereof to be let off the loose warp beam.

11. The process of providing an extra length on a loose warp thread which includes the step or steps of anchoring a loose warp thread in the ground weave and then applying pressure to said thread adjacent its point of anchorage and in the direction of the woven fabric to force an extra length of thread from off the loose warp beam.

12. The process of producing an extra length on a loose warp thread which includes the step or steps of anchoring the loose warp thread in the ground weave, and causing a plurality of picks to be moved successively against said loose thread adjacent its point of anchorage and in a direction to cause an extra length thereof to be let off the loose warp beam.

In testimony whereof I have hereunto signed my name.

JAMES R. LISTER.
